(57) **CLAIM**

We claim the ornamental design for a foldable padding, as shown and described.

DESCRIPTION

FIG. 1 is a perspective view of a foldable padding showing our new design;

FIG. 2 is an enlarged perspective view of detail 2 in FIG. 1;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The dash-dot-dash broken lines depict boundaries of the claim and form no part of the claimed design. All other evenly spaced dash-dot broken lines illustrate portions of the foldable padding that form no part of the claimed design.
